US0D1104772S

(12) **United States Design Patent** (10) **Patent No.:** **US D1,104,772 S**
(45) **Date of Patent:** **** Dec. 9, 2025**

(54) **DISPENSER**

(71) Applicant: **Method Products, PBC**, San Francisco, CA (US)

(72) Inventor: **Sean McGreevy**, Oakland, CA (US)

(73) Assignee: **Method Products, PBC**, San Francisco, CA (US)

(**) Term: **15 Years**

(21) Appl. No.: **29/932,341**

(22) Filed: **Mar. 13, 2024**

(51) **LOC (15) Cl.** **09-01**

(52) **U.S. Cl.**

USPC **D9/682**

(57) **CLAIM**

The ornamental design for a dispenser as shown and described.

DESCRIPTION

FIG. 1 is a top perspective view of a dispenser showing the claimed design;

FIG. 2 is a bottom perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

The broken lines in the figures show portions of the dispenser that form no part of the claimed design.

1 Claim, 7 Drawing Sheets
